UNITED STATES PATENT OFFICE

MARCUS A. HEYMAN, OF NEW YORK, N. Y.

ORNAMENTAL SHOE

Application filed April 4, 1928. Serial No. 267,225.

My present invention relates generally to the manufacture of shoes, and has particular reference to the ornamental type of ladies' shoes.

It is one object of my present invention to provide an ornamental shoe of this character wherein the upper thereof is constructed in a novel and attractive manner which imparts a unique and pleasing appearance to the shoe and which is at the same time highly satisfactory from the standpoint of wear.

It is another object of my invention to provide a shoe of the character mentioned wherein the upper, and particularly the vamp, is constituted of a novel type of sheet material which renders the cost of manufacture extremely low and produces a finished article of unusual and hence attractive character.

The type of ornamental shoe to which my invention particularly relates embodies upper portions which are perforated or provided with groups or areas of interstices, such a construction resulting in extreme lightness, airiness, and popular pleasing appearance. It is a feature of my invention to constitute such uppers of sheet material formed of intertwined or interlaced strands, the strands being of relatively light and pliable material such as paper.

It is an object of my present invention to provide a shoe upper, and particularly a shoe vamp, of such intertwined material, and to construct the material in such a manner as to render its employment practicable and satisfactory. It is a feature of my invention to provide the sheet material of strands which are so intertwined or interlaced that certain areas of the material are relatively staunch and devoid of any interstices, while other areas thereof are intertwined or braided of the same strands but in a different manner so as to provide the desired ornamental and reticulated areas. More particularly, it is a feature of my invention to provide a shoe vamp wherein the tip portion is composed of intertwined strands closely arranged, and wherein other portions are composed of the same strands braided in a different and less intimate manner. The tip portion of the

vamp is likely to be subjected to the greatest wear and is thus illustrative of those portions which are preferably intertwined or interlaced in the staunch manner referred to.

Another feature of my invention lies in providing a master blank of the intertwined or interlaced sheet material, the blank being so shaped as to be severable along predetermined lines to provide the necessary blanks for the shoe uppers. The master blank comprises alternate areas whereof one set is relatively staunch and unperfected and is formed of closely intertwined strands, and whereof the other set is ornamental in its nature and is formed of the same strands intertwined or interlaced in a different manner so as to provide the desired interstices or perforations. These different areas are so arranged on the master blank that when the shoe upper blanks are cut therefrom, those portions of the upper blanks which should embody the greatest strength, such as the tips of the vamps, will comprise the closely intertwined or interlaced areas.

For the attainment of the foregoing objects and such other objects as may hereinafter appear or be pointed out, I have constructed a shoe embodying the features of my present invention and illustrated in the accompanying drawings in which—

Figure 1 is a plan view of a master blank from which two shoe vamps may be cut as indicated by dotted lines; the dot and dash lines of this figure indicating a possible severance of the master blank whereby the blanks for the quarters of the shoe may also be cut therefrom;

Figure 2 is a fragmentary plan view, upon a greatly enlarged scale, of a portion of the blank of Figure 1; and

Figure 3 is a side elevational view of a shoe embodying a vamp and quarters constructed of the blanks shown in Figure 1.

In Figure 1, I have shown a substantially rectangular blank 10 of sheet material formed in accordance with the present invention. The entire blank is composed of intertwined or interlaced strands, the strands of the present embodiment being arranged along diagonal lines with respect to the rectangular shape 100.

of the blank. The strands forming the transverse bands or areas 11 are closely intertwined or interlaced in a manner which produces a relatively staunch area having substantially no interstices. The strands forming this area extend right through the entire blank but are intertwined or interlaced in a different manner throughout the intermediate area 12 so as to produce a relatively less staunch, yet 10 more ornamental area, which includes the spaced interstices or perforations 13.

Reference to Figure 2 will show more clearly how the strands are intertwined or interlaced in the two types of areas referred to. This enlarged view of the intertwined or interlaced material discloses the manner in which the area 11 is formed of the two sets of strands 14 and 15 arranged in intertwined or interlaced relationship along mutually perpendicular diagonal lines. As these strands enter the area 12 they are intertwined or interlaced with one another in a different manner so as to result in the production of the spaces or interstices 13.

25 The blank 10 of Figure 1 is so sized and proportioned as to be suitable for severance into two blanks 16 and 17 ultimately to be employed in the production of two shoe vamps. The blank 16 is formed by cutting 30 along the dotted line 18, and the blank 17 is formed by cutting along the dotted line 19. It will be noticed that the blanks 16 and 17 are arranged back to back, and that each one thereof includes at its tip portion an area 35 of relatively closely intertwined or interlaced material.

Referring for the moment to Figure 3, wherein I have shown a completed shoe of the character contemplated by my invention, 40 it will be noticed that the vamp embodies the tip portion 20 which is of relatively staunch and closely intertwined or interlaced material, the portion 21 to the rear of the tip being of the perforated nature previously referred 45 to. The attractive appearance imparted to the shoe by this construction will be obvious in Figure 3, and it may be pointed out that the relative methods of intertwining or interlacing the strands of the material result in the 50 production of an efficient shoe vamp which provides the tip portion 20 with sufficient strength to withstand the necessary wear while at the same time producing a vamp which is light in weight, airy, and attractive 55 in appearance.

This general nature of my invention permits of a number of modifications. For example, where the vamp is attached to the sole 22, it may be reinforced by intertwining or 60 interlacing strands along this line in the same closely intertwined or interlaced manner as are the areas 11. This would require that the blank 10 of Figure 1 be so constructed that the areas 11 extend laterally along the outer 65 portions of the lines 18 and 19. Similarly,

the two quarters 23 of the shoe may be formed of the same general type of material and may be rendered sufficiently strong and at the same time ornamental by suitably designing the blank from which they are cut. If the master blank 10 of Figure 1 is suitably shaped and proportioned, a pair of blanks 24 70 may be rendered available for providing the two quarters of one shoe, and a pair of similar blanks 25 may be rendered available for forming the two quarters of a second shoe. Whether these blanks 24 and 25 are to be entirely closely intertwined or interlaced or alternately closely and loosely intertwined or interlaced depends entirely upon the design of the shoe desired. For example, in the shoe of Figure 3, the quarter 23 is closely intertwined or interlaced throughout substantially its entire area, with the exception of a small medial area 26 which is intertwined or interlaced in the different manner which produces the group of interstices. 85

For similar reasons, the center portion of the blank 10 might be employed for providing the quarter or quarters.

In general, it will thus be obvious that I do not mean to limit myself to any particular alternate arrangement of the differently intertwined or interlaced areas. The master blank 10 may be modified in a number of ways to efficiently permit of the cutting thereof of the various blanks of the shoe upper. Dependent upon requirements, the closely intertwined or interlaced areas will be positioned so that those portions of the finished shoe which are preferably of more staunch and unperforated character will embody these areas at the proper places.

Nor do I mean to limit myself to the particular manner in which the strands are intertwined or interlaced, except in so far as hereinbefore stated. Certain areas are so constructed as to be relatively close and devoid of interstices, while other areas are intertwined or interlaced in a different manner so as to embody the desired ornamental and perforated character of material.

In general, it will be understood that changes in the details herein described and illustrated for the purpose of explaining the nature of my invention may be made by those skilled in the art without departing from the spirit and scope of the invention as expressed in the appended claims. It is therefore intended that these details be interpreted as 115 illustrative, and not in a limiting sense.

The intertwining or interlacing of the strands is preferably such as is disclosed on the drawings, although variations therefrom may still fall within the scope of the invention. Such intertwining or interlacing may perhaps be best designated as braiding, particularly if there be no selvage thread along the edge of that part of the blank which is closely intertwined or interlaced. By the 120

term "intertwined" as used in the claims, I intend to cover a fabric such as is illustrated on the drawing and equivalents thereof no matter what technical term may be used to 5 designate the method of manufacture.

Having thus described my invention and illustrated its use, what I claim as new and desire to secure by Letters Patent is—

1. In an ornamental shoe, a vamp comprising a sheet material formed of intertwined paper strands, the strands of the tip portion of said vamp being closely intertwined so as to provide a substantially unperforated and relatively staunch area, and said strands extending into adjacent portions of said vamp and being differently intertwined in said adjacent portions so as to provide an area embodying a group of interstices.

2. For use in the manufacture of ornamental shoe uppers, a blank of sheet material formed of intertwined strands, said blank comprising alternate areas whereof one set is relatively staunch and unperforated and is formed of closely intertwined strands, and 25 whereof the other set is ornamental and perforated and is formed of the same strands intertwined in a different manner.

3. A master blank of the character described and adapted to be severed into a pair 30 of blanks for the manufacture of shoe vamps, said master blank comprising sheet material formed of intertwined strands, said sheet material including spaced areas wherein the strands are intertwined in a relatively close 35 manner, and an intermediate area wherein the same strands are intertwined in a different manner which provides a series of interstices in the material, said master blank being so shaped and sized that two shoe vamps may be 40 cut therefrom, each of said vamps having a tip portion which extends into one of said closely intertwined blank areas.

4. For use in the manufacture of ornamental shoe uppers, a blank of sheet material 45 formed of intertwined strands, said blank comprising alternate areas whereof one set is closely intertwined, unperforated, and relatively staunch, and whereof another set is open-work-intertwined and ornamental, a 50 relatively stanch part being adapted for forming a part of a shoe upper subjected to greater wear and a loosely intertwined part being adapted to form a part of a shoe upper subjected to less wear.

5. For use in the manufacture of ornamental shoe uppers, a blank of sheet material 55 formed of intertwined strands, said blank comprising alternate areas whereof one set is closely intertwined, unperforated, and relatively staunch, and whereof another set is open-work-intertwined and ornamental, both 60 the closely intertwined and open-work-intertwined parts being intertwined of the same strands, a relatively staunch part being 65 adapted for forming a part of a shoe upper

subjected to greater wear and a loosely intertwined part being adapted to form a part of a shoe upper subjected to less wear.

6. A blank of sheet material formed of intertwined strands and adapted to be severed into shoe upper blanks which include a blank 70 for a shoe vamp, certain portions of said material including the portion which is adapted to constitute the tip portion of said vamp blank being closely intertwined to provide 75 relatively staunch areas devoid of interstices, and other portions of said material being open-work-intertwined of the same strands, said closely intertwined areas and said open-work-intertwined area being intertwined 80 only of the same strands.

7. In an ornamental shoe, a vamp comprising sheet material formed of intertwined strands, said strands being so intertwined 85 that a portion of said vamp which is subjected to lesser wear is open-work-intertwined and provided with a group of interstices, while another portion thereof which is subjected to greater wear is closely intertwined 90 and devoid of interstices, the different kinds of intertwining being of the same strands.

8. In an ornamental shoe, a vamp comprising sheet material formed of intertwined paper strands, said strands being so intertwined 95 that a portion of said vamp which is subjected to lesser wear is loosely intertwined and provided with a group of interstices, while another portion thereof which is subjected to greater wear is closely intertwined and devoid of interstices, the different kinds 100 of intertwining being of the same strands.

9. In an ornamental shoe, an upper comprising sheet material formed of intertwined strands, a portion of said material being 105 closely intertwined at a point where the shoe is subjected to greater wear, the same strands being open-work-intertwined at a point where the shoe is subjected to less wear.

In witness whereof I have signed this specification this 17 day of March, 1928.

MARCUS A. HEYMAN.
